US0D1022195S

(12) **United States Design Patent** (10) **Patent No.:** **US D1,022,195 S**
(45) **Date of Patent:** ** *Apr. 9, 2024

(54) **DREDGE DEVICE**

(71) Applicant: **DCSTAR INC**, New York, NY (US)

(72) Inventor: **Ligui He**, New York, NY (US)

(73) Assignee: **DCSTAR INC**, New York, NY (US)

(*) Notice: This patent is subject to a terminal disclaimer.

(**) Term: **15 Years**

(21) Appl. No.: **29/791,694**

(22) Filed: **Jan. 29, 2022**

(30) **Foreign Application Priority Data**

Aug. 30, 2021 (CN) 202130568520.3

(51) **LOC (14) Cl.** **24-02**

(52) **U.S. Cl.**

(57) **CLAIM**

The ornamental design for a dredge device, as shown and described.

DESCRIPTION

FIG. 1 is a front view of a dredge device showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines depict portions of the dredge device that form no part of the claimed design.

1 Claim, 7 Drawing Sheets
